UNITED STATES PATENT OFFICE.

CHARLES F. PACKARD, OF GREENWICH, CONNECTICUT.

SAWING-MACHINE.

Specification of Letters Patent No. 11,257, dated July 11, 1854.

To all whom it may concern:

Be it known that I, CHARLES F. PACKARD, of Greenwich, in the county of Fairfield and State of Connecticut, have invented a new and Improved Sawing-Machine; and I do hereby declare that the following is a full, clear, and exact description of the same, reference being had to the annexed drawings, making a part of this specification, in which—

10 Figure 1, is a plan or top view of my improved machine. Fig. 2, is a longitudinal vertical section of the frame of the machine, showing the device by which the horizontal circular saws are operated. Fig. 3, is also a longitudinal vertical section of the frame, showing the inner side of the frame opposite to the inner side shown in Fig. 2. This view shows the device by which the reciprocating motion is given the carriage on which the log is secured. In both Figs. 2, and 3, the plan of section is through the center of the frame.

15

20

Similar letters of reference indicate corresponding parts in the several figures.

25 This invention relates to a new and improved sawing machine for sawing laths, pickets, etc., direct from the log, and consists in the employment or use of a vertical saw, or a vertical reciprocating saw, and a series of horizontal circular saws, the horizontal saws being placed on one shaft at a suitable distance apart, said shaft being attached to a vibrating frame operated in a

30

35

40

peculiar manner, as will be hereafter shown, so that the horizontal saws will be thrown outward from the carriage and log, when the carriage and log are moved in one direction, and thrown in toward the carriage and log when the carriage and log are moved in the opposite direction.

When the horizontal saws are thrown in toward the log, they cut into the log the distance the width of the laths, pickets, or other article to be sawed from the log are intended to be, and when the horizontal saws are thrown from the log upon the return motion of the carriage, the vertical circular saw cuts the laths, pickets, or other article from the log.

To enable others skilled in the art to make and use my invention, I will proceed to describe its construction and operation.

A, represents a rectangular frame, constructed in any proper manner, and having on its upper part, a carriage, B, shown in

all of the figures. Underneath the carriage, B, there is a rack, C, shown in Fig. 3.

D, is a circular saw attached to a horizontal shaft, E, which shaft runs in suitable bearings, (a), on a small frame, F, attached to the frame, A, see Fig. 1. The saw, D, is placed near the frame, A, as shown in the above figure.

E', Fig. 1, is a shaft hung in the small frame, F, and having a driving pulley, G, upon it, a belt, (b), passing around the driving pulley, G, and around a pulley or drum, (c), on the saw shaft, E. H, Fig. 1, is a shaft, also hung in the frame, F, and parallel with the shaft, E'. On the shaft, H, there is a drum, (d), against which the belt, (b), bears sufficiently hard to cause the shaft, H, to rotate.

I, Fig. 1, is a shaft placed in front of the small frame, F, and having a pulley, J, on its outer end, and a pinion, K, on its inner end. A belt, (e), passes around the pulley, J, and around the drum, (c), on the shaft, E. The pinion, K, gears into a toothed wheel, L, which is hung at one end of a shaft, M, in the frame, A, the shaft, M, extending entirely across the frame, A, as shown in Fig. 1. The inner end of the shaft, M, is fitted in a lever, N, having its fulcrum at (f), the lever being attached to the inner side of the frame, A, see Fig. 3. On the inner end of the shaft, M, there is a pinion, see Figs. 1, and 3, which, when the end of the lever, N, in which the shaft, M, rests is raised, gears into the rack, C, underneath the carriage, and when the end of the lever, N, is depressed, the pinion, (g), gears into a pinion, (h), attached to the inner side of the frame, A, see dotted lines in Fig. 3, the pinion, (h), gears into a pinion, (i), which pinion, (i), gears into a pinion, (j), communicating with the rack, C.

O, Figs. 1, and 3, is a lever, having its fulcrum at (k), and attached to the inner side of the frame, A, shown clearly in Fig. 3. At the inner end of the lever, O, there is a spring, (l), and a catch, (m), by which the lever, N, is supported, so as to allow the pinion, (g), to gear into the rack, C. At the outer end of the lever, O, there is an inclined plane, (n), more particularly shown in Fig. 3.

P, are a series of horizontal circular saws, placed at suitable distances apart upon a shaft, Q, which has its bearings in a vibrating frame, R, shown in Fig. 1. The saws,

P, are driven by means of a belt, (o), Fig. 1, which passes around the shaft, Q, and around the drum, (d), on the shaft, H.

S, Figs. 1, and 2, is a rod which is attached to the vibrating frame, R, and to a lever, T, on the inner side of the frame, A. The lever, T, has its fulcrum at (p), as shown in Fig. 2, and by dotted lines in Fig. 1.

10 U, Fig. 1, is a movable or sliding bed on the carriage, B, see Fig. 1. This bed, U, is provided with clamps, (g), (g), at one end, between which the log, V, to be sawed is secured. The log, V, is represented by dotted lines in Fig. 1. The bed, U, is provided with racks, (r), (r), the upper parts of which are shown in Fig. 1, and pinions, (s), (s), on a shaft, W, gear into said racks. On the outer end of the shaft, W, there 20 is a ratchet wheel, X, into which a pawl, (t), attached to a movable frame, Y, catches.

Operation: The log, V, to be sawed is secured between the clamps, (g), (g), on the bed, U, motion being communicated to the 25 shaft, E', the circular saw, D, is made to rotate by means of the belt, (b), passing around the pulley, G, and drum, (c). Motion is given the carriage, B, by means of the pinion, K, gearing into the toothed 30 wheel, L. The pinion, (g), gears either into the rack, C, underneath the carriage, B, or into the pinion, (h), see Fig. 3. Suppose the pinion, (g), to be depressed on gearing into the pinion, (h), the carriage 35 will then be moved in the direction indicated by the arrow 1, shown in all the figures, and the circular horizontal saws will cut in the log, V, the required depth, as the carriage, B, and log, V, is moved along. The saws, 40 P, are held in the proper position by means of a spring, Z, Figs. 1 and 2, which bears against the lever, T, and keeps the saws at the proper point, so as to cut the requisite depth into the log. When the carriage, B, 45 has moved the length of the log in the direc-

tion of arrow 1, a stump, (u) attached by a pivot to the carriage, acts against an inclined plane, (w), at the outer end of the lever, T, and forces the saws, P, outward from the log, the vibrating frame, R, being retained in an outward position by means of a spring catch, (x), which passes over the inner end of the lever, T, shown clearly in Fig. 1. A stump (y), also acts at the same time upon the inclined plane, (n), on the lever, O, and causes the catch, (m), to raise the outer end of the lever, N, and throw the pinion, (g), in gear with the rack, C, underneath the carriage, B, which, in consequence, moves in a reverse direction, 60 see arrow 2, and the vertical saw, D, cuts off the laths, pickets, or other articles from the log, V, it being understood that the horizontal saws, P, determine the width of the article sawed by the depth they enter the 65 log.

The log, V, is properly fed toward the saws, P, at every vibration or stroke of the carriage, B, by means of the pawl, (t), operating the ratchet, X, said pawl being 70 moved by means of a stump, (z), acting against an inclined plane, (a'), attached to the frame, A, as shown in Fig. 1.

I do not claim the vertical saw and horizontal saws, operating as herein shown, irrespective of the peculiar arrangement and mechanism, whereby the motion is given the vibrating frame.

What I claim therefore, and desire to secure by Letters Patent, is—

The combination of a vertical circular saw D, or a vertical reciprocating saw, and the horizontal circular saws P, when said saws are constructed, arranged and operated in the manner, and for the purpose as herein shown and described.

CHARLES F. PACKARD.
